UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR CARPET.

SPECIFICATION forming part of Design No. 12,104, dated January 4, 1881.

Application filed November 26, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration, forming a part of this specification.

10 The design is composed of the angular stripes A, partially interwoven, the stripes B, arranged to form a number of rectangles, and the masses of foliage and flowers arranged upon the ground of the carpet and partially covering the stripes A B.

15

I claim—

The design for a carpet, substantially as described.

In testimony whereof I have signed my name to this specification, in the presence of two 20 subscribing witnesses, this 30th day of November, A. D. 1880.

THOMAS J. STEARNS.
